UNITED STATES PATENT OFFICE.

CHARLES BENTON STRANG AND JOHN F. STRANG, OF LINDENWOOD, ILLINOIS.

PRIMER FOR INTERNAL-COMBUSTION ENGINES.

1,108,411.

Specification of Letters Patent.

Patented Aug. 25, 1914.

Application filed February 6, 1913. Serial No. 746,556.

To all whom it may concern:

Be it known that we, CHARLES B. STRANG and JOHN F. STRANG, citizens of the United States, residing at Lindenwood, in the county of Ogle and State of Illinois, have invented certain new and useful Improvements in Primers for Internal-Combustion Engines, of which the following is a specification.

10 The object of this invention is to construct a priming means for use when starting an internal combustion engine, the priming means to give an added mixture of gasoline and air to the regular mixture coming from a carbureter, and to so recharge the regular mixture at a point in its passage to the several cylinders, before it is distributed through the manifold sections to said cylinders.

20 In the accompanying drawings, Figure 1 shows our improved primer as applied to the engine of a motor vehicle. Fig. 2 is an enlarged vertical section through the intake manifold illustrating the primer distributing head. Fig. 3 is a plan section on the line 3—3 of Fig. 2.

The embodiment of our improved primer as shown in the drawings, is applied to an internal combustion engine of the multi-cylinder type and such as are used in motor vehicles, having a dash 5 and radiator 6 located in relation to the engine.

35 The intake side of the engine is shown with the intake manifold having side wing sections 7 leading to the several cylinders and a vertical section 8 adapted to lead to a carbureter as is well understood in the art.

40 Mounted on the dash 5 is a tank 9 suitable for containing gasoline, kerosene, or such liquid as is to be used in the priming. The outlet from the tank is controlled by the hand-cock 10, which communicates with a pipe 11 leading to the main section of the intake-manifold, said pipe 11 being inclined toward the dash so as to allow gasoline to pass readily to said manifold section, and has a receptacle 12 which retains a certain amount of gasoline. An adjustable air-valve 13 of a common type communicates with the pipe 11 in such a manner as to mix readily with gasoline coming from the tank 9.

45 A distributing head 14 is located within the main section 8 of the intake-manifold, and is supported therein by the connection 15 which also serves as a passage from the

50 supply pipe 11 to the distributing head. The distributing head as illustrated in this case, is of an elongated cylindrical shape, tapered toward its lower end, is formed with a receptacle 16 and has a plurality of discharge openings 17 communicating with the receptacle 16 and discharging at a point within or adjacent to the divergence of the side wing sections 7 of the manifold. Guide-pins 18 hold the distributing head centrally in the manifold.

55 When the primer is to be used, that is, when it is to co-act with the regular intake gas mixture to enable the engine to start immediately responsive to the cranking thereof, the hand-cock 10 is opened allowing gasoline to enter receptacle 16. Upon cranking the engine, the suction thereof will draw the regular mixture of gasoline from the carbureter through the manifold, the mixture passing around the sides of the distributing head, and said regular mixture will receive an added and commingling charge of gasoline gas at the point of divergence of the manifold sections, said added charge being drawn from the radially spaced opening 17 and comprising a mixture of gasoline and air received from the receptacles 16 and 12 and air valve 13. 60 This added charge of fuel gas will enrich and remix with a sufficient charge of air, the charge being drawn to the cylinders from the carbureter so as to put said charge in condition for immediate firing thus 65 eliminating the defects of the regular initial charges being insufficiently and improperly mixed, which causes continued cranking to start the engine and results often in the flooding of the cylinders with the charge 70 of fuel in an unmixed state.

75 We claim as our invention—

80 1. A primer for internal combustion engines adapted to charge an explosive mixture passing through the main intake section of an engine manifold, with fuel gas, the primer having discharge openings located at points adjacent the divergence of said section to several cylinders, said openings adapted to deliver a discharge at an 85 angle conforming with and in the direction of said divergence.

90 2. A primer for internal combustion engines comprising a distributing head located within the main intake section of an engine manifold, the distributing head being a fuel receptacle formed with a stream 95

line body and having openings adjacent its top end, and means for admitting fuel and air to the receptacle.

3. A primer for internal combustion engines comprising a distributing head located within the main intake section of an engine manifold and said head having discharge openings therein, a fuel supply tank having a connection therewith, an auxiliary fuel pocket located on said connection between the tank and distributing head, a valve for controlling the supply of fuel to said distributing head, and an air valve adapted to communicate with the distributing head.

4. A primer for internal combustion engines comprising a receptacle located within

the main section of an engine manifold, the receptacle having openings communicating with the manifold, means for admitting fuel to the receptacle, and an air valve communicating with the receptacle, the air and fuel adapted to be drawn from said receptacle in the form of a vapor, by the suction of the engine.

In testimony whereof we have hereunto set our hands in presence of two subscribing witnesses.

CHARLES BENTON STRANG.
JOHN F. STRANG.
